SAMUEL MORTIMER, OF LEICESTER, MASSACHUSETTS, ASSIGNOR TO
CHARLES W. GILBERT.

Letters Patent No. 61,754, dated February 5, 1867.

IMPROVEMENT IN MECHANISM FOR OPERATING THE PICKER-STAFFS OF LOOMS.

The Schedule referred to in these Letters Patent and making part of the same.

KNOW ALL MEN BY THESE PRESENTS :

That I, SAMUEL MORTIMER, of Leicester, in the county of Worcester, and Commonwealth of Massachusetts, have invented a certain new and useful Improvement in Looms; and I do hereby declare that the following is a full, clear, and exact description of the same, reference being had to the accompanying drawings, forming a part of this specification, in which—

Figure 1 represents a front view of so much of a loom as is necessary to illustrate my invention; and Figure 2 represents a cross-section on line A B.

In the drawings, A A A' A' represent the frame pieces of the loom, B the lay, and C C the picker-staffs. The above parts are of common construction, and do not require a detailed description.

My improvement relates to the mechanism for operating the picker-staffs C C. Many different devices have been devised for operating the picker-staffs of looms, to the use of all of which more or less objections exist, and my improvement is designed to obviate such objections. The picker-staffs C C are connected to straps D D, which pass around upright friction-pulleys E E, and are connected to pieces a a, hinged to the top of the arms F F, as fully shown in the drawings. Arms F F are of peculiar construction, their lower ends being made in a curved or circular form, as shown in fig. 2, and arranged to turn freely upon journals or stands, b b, fastened to the lower side pieces of the loom, or to projections, c c, thereon. G is a horizontal shaft, upon which arms, H H, are fastened, one at each end of the shaft, and so arranged that their friction-rolls, e e, will strike into the curved parts, f, of their respective arms, F, and by their action upon the curved ends d d of arms F F, throw back alternately the upper end of arms F, as shown in red lines in fig. 2 of the accompanying drawings, and thus, through the connections a and D, give the necessary motion to the picker-staffs C C, to throw the shuttle back and forth at the proper times. By the use of arms F F, made in the peculiar manner shown, and arranged in respect to shaft G and arms H, as described, an easy and effective motion is imparted to the picker-staffs C C, while the action upon shaft G does not force said shaft alternately endwise, as is the case in some devices heretofore in use for operating the picker-staffs of looms. The upper ends of arms F F are provided with a series of holes, 1 1, whereby straps, D, can be adjusted to give a greater or less throw to the picker-staffs C C.

Having described my improvement in power looms, what I claim therein as new, and desire to secure by Letters Patent, is—

The combination, with the arms or tappets H, mounted at angles with respect to each other upon a shaft, G, of the peculiarly constructed curved levers or arms F, arranged to operate the picker-staffs substantially as shown and set forth.

SAMUEL MORTIMER.
